UNITED STATES PATENT OFFICE.

JOSEPH BLOWER DRING, OF BOSTON, ENGLAND.

DESIGN FOR A CARTON.

Application filed October 29, 1923. Serial No. 7,612. Term of patent 14 years.

To all whom it may concern:

Be it known that I, JOSEPH BLOWER DRING, a subject of His Majesty the King of Great Britain, residing at 18, Witham Bank, Boston, Lincolnshire, England, have invented a new and original Design for Cartons, of which the following is a specification, reference being made to the accompanying drawings, forming part thereof.

Figure 1 is a perspective view of a carton, for peaches for example, shewing my new design.

Figure 2 is a back view of the carton shewn in Figure 1.

Figure 3 is a plan view.

I claim:

The ornamental design for a carton as shown.

In testimony whereof, I have affixed my signature.

JOSEPH BLOWER DRING.
